UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SHOES.

Application filed April 10, 1919. Serial No. 288,958.

To all whom it may concern:

Be it known that I, ERASTUS E. WINKLEY, a citizen of the United States, residing at Lynn, in the county of Essex and State of Massachusetts, have invented certain new and useful Improvements in Machines for Operating on Shoes; and I do hereby declare the following to be a full, clear, and exact description of the invention, such as will enable others skilled in the art to which it appertains to make and use the same.

The invention relates to machines for operating on the marginal portions or edges of shoe soles, and more particularly to an edge setting machine for automatically burnishing or setting the edges of shoe soles.

The machine in which all the features of the invention have been embodied is a twin machine provided with two jacks alternately movable from receiving to working position, and also provided with two sets of tools or irons for operating on the soles of the shoes on the respective jacks. Each set of tools comprises a toe iron which is given a traversing movement about the toe of the shoe sole, two forepart irons which are given traversing movements along the forepart between the toe and ball line on opposite sides of the shoe sole, and two shank irons which are given traversing movements along the shank between the ball line and the heel line on opposite sides of the sole. The path of travel of each of the forepart and of each of the shank irons is adjusted in accordance with the shoe to be operated upon by means of gages which are brought by the operator into register with the ends of the ball line and the ends of the heel line of the shoe while the jack is in receiving position, and which are so connected with the traversing mechanism for the irons that the traverse of each iron will correspond to the length and position of the forepart and shank of the shoe when the shoe is brought into working position by the inward movement of the jack. Mechanism is provided for supplying the power for producing the preliminary manual adjustment or movement of the gages and

50 adjustment of movement of the gages and connected mechanism, thus relieving the operator of the major part of the muscular exertion which would otherwise be required, and contributing to the ease and rapidity of such adjustment. The mechanism preferably 55 comprises means for shifting the gages

in either direction, so arranged that the gages may be connected therewith and disconnected therefrom by the operator at any point within their range of movements to effect the required manual setting of the gages and traversing mechanism, preparatory to the automatic operation of the tools upon the shoe.

Each set of tools is withdrawn from the shoe at the completion of its operation thereon, preparatory to the withdrawal of the jack to receiving position, and is retained in retracted position until the corresponding jack is again moved into working position. To avoid possible injury and unnecessary wear of the tools and their operating mechanisms, means is provided for preventing the advance of the tools into working position, and also for preventing the traverse of the tools during any cycle in which the corresponding jack may advance into working position without a shoe thereon, and for resuming the normal operation of the tools upon the presentation of a shoe in working position. The two sets of tools are given their traversing movements by a single set of cams, and means is provided for automatically disconnecting each set from the cams at the completion of its operation on the shoe, previous to the withdrawal of the corresponding jack to receiving position, and for connecting each set of tools to the cams, preparatory to operating on a shoe after the corresponding jack has been advanced to working position. The means for preventing the advance of the tools into working position, and for preventing their traversing movements in the absence of a shoe upon the jack, preferably comprises devices which are so controlled by a shoe engaging feeler that they are rendered active to prevent the advance of the tools, and to prevent the connection of the tools with the traversing feed cams, in case there is no shoe presented in position to be engaged by the feeler, but remain inactive to permit the normal operation of the tools in case a shoe is presented in position to be engaged by the feeler.

To permit the irons to be vibrated during their travel along the sole edge at the high speed requisite for their most efficient action, they are carried in comparatively light holders mounted to vibrate on the comparatively heavy and slowly reciprocating car- 110

riages which feed them along the sole edge. When the tools are advanced into working position each tool is guided into engagement with the sole edge by a finder guide finger 5 which rides on to the tread surface of the sole and lifts the tool into register with the sole edge, and to permit the tool to readily accommodate itself to slight variations in the vertical position of the edge it is so connected with the finder that it may move vertically with relation thereto to a limited extent. Each tool is also provided with a steering mechanism which during the travel of the tool along the sole edge varies its 10 angular position in accordance with the longitudinal curvature of the sole edge to maintain the tool substantially normal to such curve.

In addition to the features briefly outlined above, the invention also includes further features and combinations herein-after described and specified in the claims.

The invention is illustrated in the accompanying drawings, in which Figures 1 and 2 25 are collectively a front elevation of a twin sole edge setting machine embodying all the features of the invention in their preferred forms; Figs. 3 and 4 are collectively a left side elevation of the machine; Fig. 5 is a 30 plan view of the machine; Fig. 6 is a vertical sectional elevation through the left hand jack; Fig. 7 is a sectional plan view on a line passing directly above the jack slide guides, the slides being removed and the rear parts of 35 the guides being broken away; Fig. 8 is a sectional plan view on approximately line 8, Fig. 6, some of the parts above the section line being indicated in dotted lines; Fig. 9 is a horizontal sectional detail showing parts 40 of the driving mechanism; Fig. 10 is a sectional plan view showing the mechanisms for withdrawing the tools from working positions; Fig. 11 is a detail sectional plan view showing the mechanism for adjusting 45 the traversing mechanisms for the shank tools; Fig. 12 is a detail sectional elevation through the center of one of the jacks; Fig. 13 is a sectional view on line 13, Fig. 14; Fig. 14 is a sectional view on line 14, Fig. 50. 12; Fig. 15 is a detail showing the means for 55 adjusting the heel and toe posts of the jack; Fig. 16 is a detail front elevation of the devices for making the preliminary adjustment of the tools; Fig. 17 is a detail plan view of these devices; Fig. 18 is a side elevation, partly in section, showing these devices; Fig. 19 is a sectional view on line 19, Fig. 18; Fig. 20 is a sectional detail on line 60, Fig. 19; Fig. 21 is a sectional detail on line 21, Fig. 19; Fig. 22 is a sectional plan view on line 22, Fig. 19; Fig. 23 is a partial side elevation, showing the outer left hand shank tool and some of the parts associated therewith; Fig. 24 is a detail side 65 elevation showing parts of the mechanism

for traversing the shank tool; Fig. 25 is a sectional plan view on line 25, Fig. 24; Fig. 26 is a detail front elevation, partly in section, of the outer right hand shank tool and parts associated therewith; Fig. 27 is a detail sectional plan view on line 27, Fig. 23; Fig. 28 is a detail front elevation showing the lower part of the arm which carries the outer left hand forepart tool; Fig. 29 is a side elevation looking toward the right in Fig. 28; Fig. 30 is a perspective view showing one of the forepart tools and the parts associated therewith, and the arm on which they are carried; Fig. 31 is a detail side elevation showing a part of the mechanism for operating and controlling one of the toe tools; Fig. 32 is a detail side elevation showing the toe and forepart tools and the devices for withdrawing them from working position; Fig. 33 is a rear elevation of one of the toe tools and the mechanisms associated therewith; Fig. 34 is a side elevation of the parts shown in Fig. 33, looking toward the left; Fig. 35 is a sectional detail showing a part of the mechanism for vibrating the tool; Fig. 36 is a perspective view of one of the toe tools and mechanisms associated therewith; Fig. 37 is a detail plan view showing the devices for connecting and disconnecting the traversing feed cams and the two sets of tools; Fig. 38 is a detail plan view showing a part of the mechanism for preventing the movement of the tools into working position, and for preventing the traverse of the tools in the absence of a shoe; Fig. 39 is a detail sectional elevation showing the parts shown in Figs. 37 and 38; Figs. 40 and 41 are collectively a detail elevation looking from the front of the machine, and showing the mechanism for controlling and timing the movements of the cams through which the various parts of the machine are controlled and operated; Figs. 42 and 43 are collectively a plan view of the parts shown in Figs. 40 and 41; Fig. 44 is a detail plan view of certain connections shown in Fig. 43; Fig. 45 is a sectional side elevation on line 45, Fig. 40; Figs. 46 and 47 are details of one of the driving clutches; Fig. 48 is a sectional detail on line 48, Fig. 43; Fig. 49 is an elevation looking toward the left in Fig. 48; and Fig. 50 is a detail of the treadle controlling cam.

In operating the twin machine shown in the drawings, the operator places a shoe upon the jack, which is in receiving position, positions the shoe on the jack, and positions the jack upon the jack slide and makes the preliminary adjustment of the forepart and shank tools, after which this jack is advanced into working position, while the other jack is returned from working to receiving position. When the jack reaches working position the corresponding tools are engaged with the sole edge and

are connected with the traversing mechanism so that they operate upon the shoe carried by the jack while the operator is replacing the finished shoe upon the other 5 jack with another shoe, and is making the requisite preliminary adjustments.

The construction of the jacks is shown in Figs. 12 to 15. Each jack is provided with a toe post 2 carrying the usual toe support, 10 and a heel post 4 carrying the usual spring-operated last pin. In order that the heel and toe posts may move independently to accurately position the shoe sole against the gages which determine its vertical position 15 upon the jack, they are pivoted at their lower ends to the opposite ends of the lever 6, which is in turn pivoted to the hand lever 8 through which the operator brings the shoe against the gages. The hand lever is 20 locked in the position to which it is moved by the operator by a spring-pressed latch 10 arranged to engage a ratchet segment 12. The heel and toe posts are locked in position by a pivoted clamp plate 14, the upper 25 end of which bears against the side of the toe post, and the lower end of which is connected by a link 16 with an eccentric 18 on the rock shaft 20. The link passes through a hole in the clamp plate, and carries a 30 spring 22 through which spring pressure is applied to the clamp plate when the rock shaft is operated to clamp and hold the last supporting posts in adjusted position. The base 24 of the jack is mounted for movement 35 in guides formed in the upper side of the jack slide 26, so that the jack may be adjusted forward or back on the slide to bring the toe of the shoe into such position on the slide that the toe of the shoe will always be brought to a fixed position with 40 relation to the toe and forepart tools when the jack is advanced to working position. The jack is clamped in adjusted position 45 on the jack slide by a clamping cam or eccentric 28 secured on the rock shaft 20 and arranged to engage the upper surface of the jack slide.

The position of the shoe on the jack, and the position of the jack on the jack slide, is 50 determined by a toe gage 30 adapted to engage the toe end of the shoe sole and to engage the tread surface of the sole at the toe, and a heel gage 32 adapted to engage the tread surface of the sole adjacent to the heel (Figs. 16 to 18). These gages are 55 mounted upon a rock shaft 34 upon which the toe gage is secured in fixed position, and upon which the heel gage is longitudinally adjustable to bring it into position to engage 60 shoes of different sizes. The operator rocks the shaft to bring the gages into active position, as indicated in dotted lines in Figs. 18 and 19, preparatory to jacking and positioning a shoe, and rocks the shaft into the 65 position indicated in full lines in Figs. 16

and 18 to remove the gages from active position so that they will not interfere with the movement of the jack into working position. The shaft may be held in either position by the spring-pressed latch pin 36. 70

The gages through which the operator sets the actuating mechanism for the forepart and shank tools in accordance with the shoe to be operated upon, comprise ball gages 38 adapted to be brought into register with the 75 ends of the ball lines of the shoes, and heel gages 40 adapted to be brought into register with the ends of the heel lines of the shoes (Figs. 16-22). Each gage comprises an 80 arm projecting from a hub 42 which is pivotally supported in a carriage 44 keyed to slide on a guide rod 46. The gage is held in substantially horizontal inactive position by a torsional spring 48, and is connected by a link 50 with a hand lever 52, through 85 which the operator may swing the gage down into engagement with the edge of the shoe sole, and through which he may connect the gage carriage with the shifting mechanism for shifting it forward or back to bring it into register with the ball or heel line. The shifting mechanism comprises three screw shafts arranged above and parallel to the guide rods 46, the outer shafts 54 being continuously driven in a direction to 90 shift the gages outwardly, and the inner shaft 56 being continuously driven in a direction to shift the gages inwardly. Each hand lever is provided with a yoke-shaped hub 58 mounted to turn and slide on a shaft 54, and straddling a bearing 60 on the corresponding carriage 44, which is also adapted to slide on the shaft. One hub 58 is provided with a groove 62 engaging a pin projecting from one end of a bell crank lever 64 which is pivoted on the corresponding carriage 44, and the other end of which is provided with a slot engaging a pin projecting upward from a coupling slide 66 mounted in the carriage. The coupling slide 100 is provided at its opposite ends with teeth adapted to engage either the screw shaft 56 105 or one of the screw shafts 54 when shifted from its neutral position, in which it is out of engagement with both shafts. The web connecting the hubs 58 of the hand lever is provided with a slot indicated in dotted lines at 68 in Fig. 18, which is provided with a flaring mouth at its upper end and is adapted 110 to engage a pin 70 projecting from the bearing 60 of the carriage 44. When the handle and corresponding gage are in raised position, the slot and pin hold the handle and connected coupling slide in neutral position, as indicated in Fig. 17. When the handle and gage are in this position the corresponding carriage 44 is locked against movement in either direction by a double 115 acting roller clutch indicated at 72 in Fig. 20, which comprises two spring-pressed rolls 120

interposed between two oppositely inclined surfaces on the carriage and the top of the key in the rod 46. The rolls are separated to release the carriage when the carriage is to be shifted by a spreader 74 on the inner end of a rock shaft 76, the outer end of which carries a crank pin 78 engaging a cam groove 80 in the hub 42 of the gage.

When a gage is to be shifted by the operator, he depresses the corresponding handle 52 until the gage is brought against or close to the edge of the shoe sole. During this movement of the handle and gage the cam 80 acts to unclutch the gage carriage, so that it is free to move lengthwise of the rod 46 and shaft 54, and the groove 68 moves out of engagement with the pin 70 so that the handle is free to be moved on the shaft both independently of and with the gage and gage carriage. The operator then shifts the handle forward or back, according to the direction in which he wishes to shift the gage, and thus moves the coupling slide 66 into engagement with either the shaft 56 or a shaft 54. The shaft thus connected with the gage carriage then moves the gage and handle forward or back, as the case may be, until the gage is brought to the desired point on the edge of the shoe sole. When the gage reaches this point the operator releases the handle, and the handle and gage are instantly swung up into their normal raised position by the spring 48, their upward movement being determined by the engagement of a stop lug 82 on the hub 42 with a stop pin 84 on the gage carriage. As the handle moves up, the pin 70 enters the flaring mouth of the groove 68 and shifts the handle lengthwise of the shaft 54 into neutral position, thus disengaging the coupling slide 66 from the screw shaft with which it has been engaged. At the same time the cam groove 80 on the hub 42 rocks the shaft 76 to release the rolls of the clutch 72 so that the gage carriage is locked in adjusted position. The operator may thus quickly shift the gages into proper position with relation to the shoe to be operated upon with comparatively little exertion, since the power requisite to move the gage carriages and connected parts in either direction is supplied by the continuously rotating screw shafts. The movement of the controller lever in the direction in which the gauge carriage is to be moved throws the power mechanism into operation to move the carriage in that direction and since the controller moves with the carriage the operator is given the impression that he is moving the carriage. This contributes to the ease, rapidity and accuracy of the adjustments. To prevent outward movement of the ball gages beyond the desired limits, safety stops 86 may be arranged to engage the corresponding bell crank levers 64, or the outer

ends of the hubs 58, during the outward travel of the feed carriages and connected parts, and thus shift the coupling slides into neutral position, should the levers or hubs be brought into engagement with the stops by the outward travel of these parts. Similar safety stops may be provided for automatically disconnecting the gage carriages from the actuating shafts at predetermined points in their travel in either direction.

The toe of each shoe is brought by the inward movement of a jack to the same uniform position with relation to the tools, which is determined by the fixed toe gage. The forepart tools should therefore travel inward to a fixed point, and should travel outward to a point varying with the position of the ball line, while the shank tools should travel inward to a point varying with the position of the ball line and should travel outward to a point varying with the position of the heel line. The forepart gages are accordingly connected to the actuating mechanism of both the forepart and shank tools to vary the length of the feeding strokes of the tools, and thus adjust the outward stroke of the forepart tools and the inward stroke of the shank tools in accordance with the position of the ball line. The heel gages are connected to supports for the shank tool carriages to vary the position of the supports, and thus adjust the outward strokes of the shank tools in accordance with the position of the heel line. In order that the inward or outward adjustment of the supports may not change the points at which the inward travel of the tools terminates, the heel gages are also connected to the actuating mechanism for the shank tools to vary the length of the stroke of the tools in accordance with the adjustment of the supports. Thus if the supports are adjusted inward, the strokes of the tools are so shortened that the inward movements will end at the same points which were determined by the adjustment of the forepart gages. If the supports are adjusted outward the strokes of the tools are lengthened accordingly, so that their inward movements will end at the same point.

Each forepart tool is carried in the upper end of an arm 88, the lower end of which is pivoted at 90 to a rocking base 92 (Figs. 1, 2, 4, 6, 28, 29 and 37). The trunnions 94 about which the base rocks are so arranged that the tool travels in a curved path corresponding to the lengthwise curvature of the forepart of the shoe sole. Springs 96 are connected to the arms 88, and tend to force the upper ends of the arms toward the shoe. The mechanism for rocking the base 92 and thus feeding the tool along the shoe sole comprises an arm 98 secured to one of two rock shafts 100, and slotted to receive an adjustable slide 104 (Figs. 4, 7 and 8). The slide carries a pivot block 106 which engages

a slot in a vertically movable horizontal bar 108. The bar is connected to the end of an arm 110 projecting from the rocking base 92, and is maintained in a horizontal position 5 during its vertical movements by a parallel link 112, one end of which is pivoted to a depending arm on the bar, and the other of which is pivoted an equal distance below the trunnions 94 on which the base is mounted. 10 The position of the slide in the slotted arm, and consequently the extent of feeding movement transmitted through the rock shaft and arm to the tool is adjusted through a slide 114 mounted on rods 116, and provided with 15 a vertical slot engaged by a projection 118 on the slide 104. The slide 114 is moved by movement of the corresponding forepart gage through a rack 120 on the gage carriage, which engages a gear 122 secured to a 20 shaft 124, the lower end of which is connected by a shaft 126 and universal joints with a gear 128 which engages a rack 130 on the slide (Figs. 6, 7, 16, 18 and 22). The two rock shafts 100 corresponding to the two 25 jacks are independently actuated through mechanism which will be hereinafter described.

Each shank tool is carried on the lower end 30 of an arm 132, the upper end of which is pivoted at 134 to a rocking head 136 (Figs. 1, 3, 23, 25 and 26). The arm is forced toward the shoe by a spring 135. The head is mounted upon a supporting slide 138, and the trunnions 140 about which the head 35 swings are so arranged that the shank tool will travel in a curved path corresponding substantially to the lengthwise curvature of the shank of the shoe sole. The supporting slide 142 is mounted for movement lengthwise of the shoe, and is connected to be 40 moved by movement of the corresponding heel gage by rod 144, one end of which is connected with a bracket 146 secured to the slide, and the other end of which is connected 45 to the heel gage carriage (Figs. 3, 11, 18 and 24).

The mechanism for giving the shank tools their traversing or feeding movements comprises slotted arms 148 secured to rock shafts 50 150 which are connected in pairs by yokes 152, as shown in Fig. 11, and are rocked by mechanism to be hereinafter described. An adjustable slide 154 is mounted in each 55 arm, and carries a pivot block 156 engaging a groove in one side of the vertically movable bar 158, the other side of which is provided with a similar groove engaged by a pivot block 160 on the end of an arm 162 projecting from the rocking head 136 (Figs. 60 24, 26 and 31). The bar is supported for parallel movement by bell crank levers 164 connected by the parallel link 166. This connection between the swinging head 136 and slotted arm 148 permits the supporting slide 65 142 to be adjusted lengthwise of the shoe

without affecting the feeding stroke given to the tool by the rocking movement of the slotted arm, and also permits the slide 154 to be adjusted to vary the stroke of the tool in any position of the supporting slide 142. 70 The slide 154 is adjusted to vary the stroke of the shank tool by a slide 168 mounted on a rod 170, and provided with a vertical slot engaged by a pivot block 172 on the slide 154. The slide 168 is connected to be 75 moved by movement of either the corresponding forepart or heel gage. The differential gearing through which the slide is thus moved comprises a gear casing 174 connected to turn on the shaft 124, and provided with a segment 176 engaging a rack bar 178 which is secured to the slide (Figs. 16, 17, 25, 26 and 31). The gear casing carries two intermeshing pinions 180, one of which engages a gear 182 loosely mounted 80 on the shaft 124, and connected through an intermediate gear 184 with a rack 186 secured in the rod 144 which connects the heel gage carriage with the supporting slide 142, and the other of which engages a gear 188 85 secured to the shaft 124, and thus connected with the corresponding forepart gage carriage through the gear 122 and rack 120.

Upon movement of the forepart gage the pinions 180 are rotated through the gear 188 90 and travel around gear 182, which is stationary, thus turning the segment 176 and moving the slide 168 to vary the position of the slide 154 in the arm 148, and consequently vary the movement transmitted to 100 the shank tool from the arm 148. Upon movement of the heel gage the gear 182 is rotated, while the gear 188 remains stationary, and the pinions 180 are operated in a similar manner to vary the feeding movement imparted to the shank tool by the 105 arm 148.

The mechanisms for vibrating the various tools, and for controlling their positions on the arms by which they are carried along the sole edges, are similar in construction and mode of operation, although differing somewhat in minor details. Each forepart arm 110 is provided with a lower bearing 190 in which a vertical shaft 192 is mounted, and 115 with two upper bearings 194 in which a vertically movable rod 196 is mounted (Fig. 30). The shaft and rod are approximately in line with the point of operation of the tool, and form the pivotal supports for a 120 tool carrier frame 198 which is provided with a lower bearing 200 surrounding the shaft 192, and an upper bearing 202 surrounding the rod 196. The carrier frame is also provided with bearings 204 and 206 in 125 which a vertical shaft 208 is mounted. The tool holder 210 is provided with outwardly projecting arms 212 having bearings surrounding the shaft 208, and is mounted to oscillate about the shaft. The means for vibrat. 130

ing the tool comprises a lever 214 mounted to oscillate about the shaft 208, and provided with a slotted arm 216 embracing a stud 218 depending from the lower arm 212. The other arm of the lever is provided with a slot 220 engaged by a pivot block 222, which is engaged by a crank pin 224 adjustably mounted in the slotted head 226 which is secured to the upper end of the shaft 192. The tool 228 is provided with a cylindrical shank fitting within a block mounted to slide in the segmental guideways 230 formed in the tool holder 210, as indicated with reference to the toe tool in Fig. 34. The tool is thus free to turn in the block to accommodate itself to the lengthwise curvature of the shoe sole, while the block is free to move in the guideways to allow the tool to swing vertically about its point of operation to automatically position itself with reference to the sole edge. A spring 232 tends to hold the tool and block in normal position in the tool holder. The lower end of the rod 196 is shaped to ride on to the outer surface of the sole as the arm 88 moves forward to bring the tool into engagement with the sole edge, and the rod is connected to lift the tool holder and guide the tool into engagement with the sole edge. The connection between the rod and tool holder comprises an arm 234 provided with a boss 236 secured to the rod, and two bosses 238 and 240 which surround the shaft 208 and are connected by a web 242. The lower boss 240 underlies the outer end of the upper arm 212 of the tool holder, so that the tool holder will be lifted by upward movement of the rod 196. The parts are so arranged that the tool holder may also have a slight vertical movement with relation to the rod 196, so that the tool and tool holder may accommodate themselves to variations in the relation of the shoe edge to its tread surface during the travel of the tool and guide rod 196 along the shoe.

During the travel of the tool along the shoe sole the tool carrier frame 198 is swung about the shaft 192 and rod 196, and therefore about the point of operation of the tool, to control the position of the tool so that it will be normal to the sole edge, and so that its vibratory movements will be tangent to the sole edge. The mechanism by which the tool carrier is thus swung may for convenience be termed a steering mechanism, and comprises a pinion 244 secured to the shaft 208, and engaging a gear segment 246 secured to the arm 88. The shaft 208 also carries a steadyng roll 248 arranged to ride along the surface of a segmental bearing plate 250 which is carried by the arm 88.

The shaft 192 is continuously rotated during the operation of the machine to rapidly vibrate the tool holder and tool through a shaft 252, the upper end of which is con-

nected by a universal joint with the shaft 192, and the lower end of which is connected by a universal joint with a vertical shaft 254 mounted in the bracket which supports the rocking base 92 on which the arm 88 is mounted (Figs. 28 and 29). The lower ends of the four shafts 254 are connected by spiral gears 256 with a continuously driven horizontal shaft 258 (Fig. 8). The mechanism for rotating the steering pinion 244 comprises a telescoping shaft 260, the upper end of which is connected by a universal joint to the lower end of the shaft 208 and the lower end of which is connected to the upper end of a short vertical shaft 262. The shaft is turned to control the position of the tool carrier through a segment 264 engaging a pinion 266 which is connected with the lower end of the shaft 262 through bevel gears 268. The segments 264 for the two outer forepart tools are secured to a shaft 270 which is rocked by a cam 272 secured to a cam sleeve 274, and engaging a roll on the end of an arm 276 secured to the shaft. A spring 278 is connected to one of the segments and holds the arm in engagement with the cam. The segments 264 for the two inner forepart tools are carried by a sleeve 280 mounted to turn on the shaft 270, and connected by a yoke 282 with the hub of a lever 284, the end of which carries a roll engaging a cam 286 on the cam sleeve 274. A spring 288 connected with one of the segments 264 holds the lever in engagement with the cam.

Each shank tool 290 is mounted in a tool holder 292 in the same manner as described with relation to the forepart tool. The tool holder 292 is mounted to vibrate on a vertical shaft 294 which is mounted in bearings 296 in the tool carrier frame 298. The tool carrier frame is provided with two bearings 300 which swing and turn on a finder rod 302. The finder rod is mounted to move vertically in the bearings 304 and 306 on the shank tool carrier arm 132. An arm 308 connects the finder rod with the tool holder, and is provided with a boss 310 secured to the finder rod, and two bosses 312 surrounding the shaft 294 and connected by the web 314. The lower boss 312 underlies the upper arm of the tool holder and acts to lift the holder when the finder rod rises. There is a space between the boss 312 and the lower arm of the tool holder, so that the holder may move vertically with relation to the finder rod in accommodating itself to the edge of the sole. The lever 316 for vibrating the tool holder is mounted on the shaft 294, and is provided with a lower slotted arm embracing a stud 318 rising from the holder, and is provided with an upper slotted arm engaged by a pivot block on a crank pin 320. The crank pin is adjustably secured to a head on the lower

end of a shaft 322 which is mounted in a bearing in the arm 132, and is connected by a universal joint with a shaft 324 mounted in the sliding support 142 which carries the arm. The universal joint is located in line with the pivots 134 to permit the arms 132 to swing toward and away from the shoe sole, and in line with the trunions 140 to permit the swinging movements of the head 136 and arm 132 which feed the tool along the shoe sole. The shaft 324 is driven through a spiral gear 326 which engages a spiral drum 328. The four spiral drums corresponding to the four shank tools are driven during the operation of the machine from a continuously rotating shaft 330 through spiral gears 332 (Fig. 5).

The shaft 294 carries a pinion 334 engaging a segment 336 secured to the arm 132, and the shaft is turned to control the position of the tool carrier frame through a telescoping shaft 338 connected by universal joints with the shaft 294, and with a shaft 340 mounted in the slide 142. The upper end of the shaft 340 carries a pinion 342 engaged by a pinion 344 which is carried by the slide 142 and is driven by a shaft 346 along which it may slide as the slide 142 is adjusted. The shafts 346 are actuated through segments 348 engaging pinions 350 secured to the rear ends of the shafts (Figs. 5 and 31). The segments 348 corresponding to the two outer shank tools are secured to a rock shaft 352 which is operated from a cam 354 on the sleeve 274 through a cam lever 356 and a link 358 which connects the lever 356 with an arm 360 secured to the end of the rock shaft (Figs. 3, 4 and 5). The segments 348 corresponding to the two inner shank tools are secured to a sleeve 362, and the left end of which is connected to a lever 364 mounted on the shaft and operated from a cam 366 on the sleeve 274 through a cam lever 368 and link similar to the lever 356 and link 358.

Each toe tool 370 is mounted so that it is free to turn in a block 372 which is provided with guide rolls 374 running in the segmental guideways 376 whose center of curvature is substantially in the base of the tool (Fig. 34). The tool holder 378 is mounted to vibrate about the shaft 380 which is mounted in the bearings 382 of the tool carrier frame 384. The frame 384 is mounted to turn about the finder rod 386 which is in turn mounted in bearings in the arm 388 (Figs. 33 to 36). The finder rod is connected to lift the tool holder by the arm 390, and the tool holder is vibrated by the lever 392 and the adjusted crank 394 carried by the lower end of the shaft 396. The position of the tool carrier frame is determined by the pinion 398 on the shaft 380 and the segment 400 on the arm 388.

The upper end of the arm 388 is connected by the trunnions 402 to a head 404, so that it may be swung toward or away from the shoe sole. The head is secured to a vertical shaft 406 which is arranged approximately in line with the center of curvature of an average shoe toe, and the feeding movement about the toe of the shoe is given to the toe tool by oscillation of this shaft. The arm is forced forward toward the shoe by springs 408 supported on screw rods 410 which pass through ears 412 on the arm, and are secured in a head 414 on the lower end of the shaft 406.

The tool vibrating shaft 396 is connected through a telescoping shaft 416 and universal joints with a shaft 418 which is connected through spiral gears 420 and 422 with a spiral gear 424 on the shaft which carries the continuously rotating spiral drums 328.

In order to compensate for any change in the position of the tool carrier frame upon the tool carrying arm, due to the swinging movement of the arm about the axis of the shaft 406, the steering shaft 380 is connected through differential gearing with its actuating cam and with the shaft 406. This mechanism comprises a gear carrying carrier 426 mounted to turn about the shaft 406,

and carrying two intermeshing pinions 428 and a gear segment 430. The segment is connected by an intermediate gear 432 with a gear 434 on the upper end of a shaft 436, the lower end of which is connected by a telescoping shaft 438 and universal joints with the steering shaft 380. One of the intermeshing pinions engages a gear 440 secured to the shaft 406, and the other engages a gear 442 loosely mounted on the shaft and intermeshing with a gear 444 on a shaft 446.

The upper end of the shaft 446 carries a bevel gear 448 which is engaged by a gear 450 secured to a horizontal rod 452 (Figs. 5, 6 and 31). The shaft is rocked to steer the toe tools through a lever 454, the forward end of which is provided with a gear segment 456 engaging a pinion 458 on the end of the rod 452, and the other end of which is connected by a link 460 with a cam lever 462 carrying a roll 464 engaging a cam 466 on the cam sleeve 274.

If the toe tool were to travel in a true circle about the axis of the shaft 406, the gear 442 of the steering mechanism would be stationary, and as the shaft 406 rotates, the pinions 428 would be driven from the gear 440 and would travel about the gear 442, thus swinging the gear support 426, and through the segment 430 and gears 432 and 434 would rotate the steering shaft 380 the proper amount to maintain the radial position of the toe tool during its travel about the toe. The path of travel of the tool is not, however, a true circle, and the steering cam is so shaped that it will through the

gearing described rotate the gear 442 during the travel of the tool, and thus through the differential gearing modify the position of the tool carrier frame to maintain the tool 5 approximately normal to the edge of the shoe sole.

Each of the tools is heated by a gas jet 470 carried by the corresponding finder rod, and connected with a source of gas supply 10 through a flexible pipe 472 communicating with a passage 474 formed in the rod.

The mechanism for withdrawing the tools from the shoe sole at the completion of their operation upon the shoe preparatory to the 15 withdrawal of the corresponding jack, comprises the bail-shaped arms 476 secured to shafts 478 and arranged to engage arms 480 projecting from the shank tool carrying arms 132, arms 482 secured to shafts 484 and 20 provided with pins 486 engaging slots 488 in the forepart tool carrier arms 88, and bail-shaped levers 490 provided with cross-bars 492 arranged to engage the lower projecting ends of the steering shafts 380 for the 25 toe tool (Figs. 10, 26, 32 and 36). Each bail-shaped lever is pivotally supported upon the vertical arm of a bell crank lever 494, the other arm of which is connected by a link 496 with an arm 498 which is secured 30 to a shaft 500. The rear end of the bail-shaped lever is supported on the lower end of a link 502, the upper end of which is pivotally supported upon the shaft 500. The 35 parts are so proportioned that toward the end of its inward movement which permits the toe tool to engage the shoe, the inner end of the bail-shaped lever will move quickly downward to a position below the path of travel of the shaft 380, so that the bar 492 40 at the end of the lever will not interfere with the feeding movement of the toe tool. When the bail-shaped lever is moved outward to withdraw the toe tool its inner end will move quickly upward, so that the bar 492 45 will engage the end of the shaft 380 and carry the tool and connected parts away from the shoe. Each shaft 500 is connected with the corresponding shaft 484 by the bevel gear segments 504, and these shafts are 50 in turn connected to the corresponding shafts 478 by the pinions 506 and gear segments 508. The shafts corresponding to the right jack are rocked to withdraw or release the tools through a link 510 connecting the 55 outer end of the arm 498 to one arm of a cam lever 512, the other arm of which carries a roll 514 engaging a cam 516 secured to a cam shaft 518 on which the cam sleeve 274 heretofore referred to is loosely mounted (Figs. 4, 10, 36, 38 and 39). The shafts corresponding to the left jack are actuated through a link 520, the upper end of which is connected to a yoke-shaped lever 522, one end of which is journaled on the shaft 500 60 corresponding to the right jack, and the 65

other end of which is secured to the shaft 500 corresponding to the left jack (Fig. 10). The lower end of the link is connected to one end of a cam lever 524, similar to the cam lever 512, the other end of which carries a roll 70 engaging the cam 526 secured to the cam shaft 518.

The traversing mechanisms for the tools are operated from a toe feed cam 528, a forepart feed cam 530, and a shank feed 75 cam 532 secured to the cam sleeve 274 (Figs. 7 and 8). The toe cam engages a roll on the end of a lever 534 secured to a rock shaft 536, and provided with an upwardly projecting arm 538 which carries a coupling 80 pin 540 at its upper end (Figs. 6, 7, 37 and 39). The pin is adapted to be connected with or disconnected from the traversing mechanism of the left toe tool by a coupling hook 542 pivoted on a pin 544 in the vertical 85 arm of a lever 546 and pressed towards the pin 540 by a spring 547. The lever 546 is pivoted on the shaft 536, and has a longitudinal arm which is connected by a link 548 to a lever 550, which is in turn connected 90 by a link 552 to a bevel segment lever 554 engaging a bevel gear 556 on the end of the shaft 406 which swings the toe tool about the toe of the shoe (Figs. 5, 6, 31 and 34). The shaft 406 for swinging the right toe 95 tool is connected by similar levers and links to the horizontal arm of a second lever 546' which is pivoted on the shaft 536, and is provided with an upwardly extending arm 538' carrying a coupling pin 540' adapted to 100 be engaged by a coupling hook 542' which is carried on a pivot pin 544' in the upwardly extending arm of the lever 546'.

The forepart feed cam 530 operates a lever 558 which is similar to the toe feed 105 cam lever 534 and is loosely mounted on the shaft 536 (Figs. 7, 37 and 39). This lever has two hubs connected by the yoke 560, and two upwardly projecting arms 562 and 562' carrying coupling pins 564 and 110 564' (Fig. 37).

The lever is connected with or disconnected from the rock shaft 100, through which traversing movements are transmitted to the left forepart tools, by a coupling 115 hook 566 pivoted on a pin 568 in the upper end of a lever 570 which is mounted on the rock shaft 536. The lower end of the lever is connected by a link 572 to the lower end of an arm 574 projecting downward from 120 the hub of one of the inner arms 98 corresponding to the left-hand jack, (Figs. 6 and 7). The lever is connected to and disconnected from the rock shaft 100 corresponding to the right-hand jack by a 125 similar coupling hook 566', lever 570', link 572' and arm 574'.

The shank feed cam 532 operates a lever 576 which is similar to the feed cam lever 534 and is loosely mounted on the shaft 536. 130

The upper end of the lever carries two coupling pins 578 and 578' adapted to be engaged by coupling hooks 580 and 580' which are pivoted on pins 582 and 582' in the 5 vertical arms of two levers 584 and 584' mounted to rock on the shaft 536. The horizontal arms of levers 584 and 584' are connected by links 586 with arms 588 secured to the rock shaft 150, through which feeding movements are imparted to the shank 10 tools corresponding to the left jack and to the right jack respectively (Figs. 3, 5, 11 and 32).

The means for shifting each set of coupling hooks to connect the corresponding hooks with or disconnect them from the feed cam levers comprises three pairs of pins 590, 592 and 594 which embrace the hooks 542, 566 and 580, and are mounted in the three 20 arms 596, 598 and 600 of a yoke shaped lever 602 (Figs. 7, 37 and 39). When the coupling hooks are disengaged from the corresponding coupling pins, the hook carrying levers and the connected tool traversing mechanisms are locked in position by locking hooks arranged to engage the projecting 25 ends of the pins on which the coupling hooks are pivoted. The hook carrying lever for the toe tool is locked by a locking hook 604 formed on the arm 598 and engaging the 30 projecting end of the pin 544, while the hook carrying levers for both the forepart and shank tools are locked by a hook formed on an arm 608 of the lever 602, and engaging the projecting ends of pins 568 and 582. The shifter levers 602 are operated to alternately couple the two sets of tools with the feed cam levers by two shifter cams 610 and 612 on the shaft 518 (Figs. 6, 7 and 40 8). The cam 610 engages a lever 614 provided with two hubs surrounding the shaft 270 and connected by a yoke. An arm projecting from the left-hand hub is connected by a link 616 with the lever 602 corresponding to the left jack. The cam 612 operates the lever 602 corresponding to the right jack through a lever 618 and link 620.

After a jack has been moved from receiving to working position, the shifter mechanism is operated to engage the corresponding coupling hooks and pins and thus connect the tool traversing mechanism for that jack with the feed cams. The disengagement of the hooks and pins may be effected 50 any time after the feed cams have stopped, and before they are again started. To prevent the traversing of the tools, or their forward movement toward the jack, in case a jack is brought into working position without a shoe thereon, the operation of the shifter mechanism and the operation of the tool withdrawing mechanism is controlled from the shoe on the jack. The controlling mechanism shown comprises a shoe engaging 55 feeler arranged to engage the toe of a

shoe upon the corresponding jack, and a series of latching pawls for preventing the coupling movements of the shifter levers 602, and tool engaging movements of the tool withdrawing levers 512 and 524. The 70 shoe engaging feeler for each jack consists of a lever 622 pivoted in a bracket 624 which is hung on the shaft 500 and is held in adjusted position by screws 626 engaging a bar 628 of the machine frame (Figs. 6 and 75 32). The rear ends of the feeler levers are connected by links 630 with arms 632 secured to a rock shaft 634 (Figs. 6, 7, 38 and 39). The inner ends of the feeler levers are forced upward towards the shoe by springs 80 636 connected with the links 630. The rock shaft is provided with a third arm 638 which is connected by a link 640 with one arm of a lever 642, the other arm of which rides on a cam 644 secured to the shaft 518. The 85 cam normally holds the feeler lever in retracted position, but just after the jack comes to working position a depression in the cam passes under the roll so that the feeler may move up to a limited extent if 90 arrested by engagement with a shoe, and to a greater extent if no shoe is present.

The pawls 646 for preventing the coupling movements of the levers 602 are pivoted on the shaft 634, and are arranged to engage 95 notches 648 in the arms 596 which carry the operating pins 590 for the toe tool coupling hooks (Figs. 7, 38 and 39). The pawls 650 for preventing the tool engaging movements of the levers 512 and 524 are also pivoted on the shaft 634, and are arranged to engage 100 notches 652 in upwardly extending projections on the levers. The pawls are operated by a sleeve 654 mounted on the shaft 634. The sleeve is provided with a longitudinally 105 extending bar 656 arranged to engage the tails of the pawls 650 and the tail of one of the pawls 646. The left-hand end of the sleeve (Fig. 7) is provided with a lug 658 arranged to engage the tail of the other 110 pawl 646. The tail of each pawl is provided with a stud 660 projecting through a hole in the bar 656 or lug 658, and carrying a spring 662 which holds the tail of the pawl yieldingly against the bar or lug. The 115 sleeve is connected with the cam engaging arm of the lever 642 by a rod 664, the lower end of which is pivoted to the lever, and the upper end of which passes through a block 666 pivoted on the end of an arm 668 projecting from a hub 670 formed on the bar 656 (Figs. 38 and 39). The rod carries nuts 672 above the block 666, and a spring 674 for supporting the arm.

When the lever 642 rides into a depression in the cam 644, the rod 664 will move down with the lever, and if this movement is not arrested by the engagement of a controller lever with a shoe, the nuts 672 will strike the block 666 and will rock the sleeve 654, 125 130

thus pressing the latching pawls forward into active position. If the controller lever finds a shoe on the jack, the movement of the lever 642 and rod 664 is arrested before the nuts strike the block 666, or before the sleeve is rocked to press forward the pawls. When the pawls are pressed forward they engage arms 596 and levers 512 and 524 which are at this time in uncoupling and tool 10 retracted positions, and retain them in these positions. When the sleeve is thus rocked, due to the absence of a shoe on the jack which is brought to working position, it is retained in latching position by a latch lever 676, the vertical arm of which is arranged to engage the notched end of an arm 678 which projects from a hub at the end of the bar 656 shown at the left of Fig. 38. The latch lever engages the arm 678 immediately the pawl operating sleeve is rocked, and retains the pawls in active position while the lever 642 immediately rides out of the depression in the cam 644 and withdraws the feeler levers to normal position. During this movement of the lever the spring 20 674 yields, and the rod 664 slides through the block 666. The latch lever continues to hold the pawls in active position until just before the controller levers are again operated, when it is disengaged by a pin 680 projecting from the jack operating cam. The pawl operating sleeve is then rocked by the spring 674 to return the pawls to normal inactive position. The pawls will thus 30 be rendered active each time a jack comes to working position without a shoe, but will be inactive whenever there is a shoe on the jack which comes into working position.

40   The mechanism for moving the jacks alternately from receiving to working positions consists of two pinions 682 mounted in the upper ends of swinging arms 684 and arranged to travel along fixed racks 686, and to engage racks 688 on the jack slides 45 (Figs. 4, 6, 8, 12 and 14). The arm 684 for the left-hand jack is connected by a link 690 to the upper end of an arm 692 which is secured to a rock shaft 694. The rock shaft also carries a cam lever 696, the 50 forward end of which is provided with a roll engaging a groove in the jack operating cam 698 secured to the shaft 518. The arm 684 corresponding to the right jack is connected by a link 700 to one arm 702 of a 55 rock sleeve, the other arm 704 of which is connected by a link 706 with the cam lever 696. Through these connections the jack operating cam oscillates the lever 684 in opposite directions to alternately advance and 60 retract the jack slides.

The mechanisms for rotating the cam sleeve 274 which carries the tool feeding and steering cams, and for rotating the cam shaft 518 which carries the remaining cams, and for properly timing the rotation of the

sleeve and shaft, are illustrated in detail in Figs. 40 to 50, and indicated generally in Figs. 5 and 7. The sleeve and shaft are intermittently and alternately rotated from a clutch sleeve 708 which is loosely mounted 70 on a shaft 710 and is driven from the continuously rotating drive shaft 712 through a pinion 714 and gear 716. The clutch sleeve is provided at opposite ends with the driving members of two Horton clutches 718 and 720, the driven members of which are provided with sprocket wheels 722 and 724 connected by sprocket chains 726 and 728 with sprocket wheels on the cam shaft and cam sleeve respectively. The sprocket 730 wheels are so proportioned that one and one-half revolutions of the clutch sleeve will turn the cam shaft through one-half a revolution, or will turn the cam sleeve through a complete revolution. The driven member of the clutch 718 is carried on a sleeve 730 to which the sprocket wheel 722 is secured, and which also carries the spring operated 80 stop disc 732 which controls the engagement and disengagement of the clutch rolls 90 and a rebound stop disc 734. The driven member of the clutch 720 is secured on a sleeve 736 which carries the sprocket wheel 724 and also the roll controlling and rebound stop discs 738 and 740. The roll controlling and rebound stop discs of each clutch are provided with two pairs of diametrically opposite and oppositely facing stop shoulders indicated at 742 in Fig. 45. A stop pawl 744 and a rebound pawl 746 100 for the cam shaft clutch 718 are mounted to swing upon the timing shaft 748 for this clutch (Figs. 48 and 49). The hub of the rebound pawl is provided with a lug 750 projecting in front of the upper arm of 105 the stop pawl, and held yieldingly in engagement therewith by a light spring 752. A comparatively heavy spring 754 is connected to the upper arm of the stop pawl and tends to swing both pawls into inactive 110 position. The pawls are moved forward into position to engage the roll controlling and rebound stop discs by a cam 756 secured to the end of the timing shaft 748 and engaging the end of a cam lever 758. 115 The lever is formed on a sleeve 760 loosely mounted on a rock shaft 762, and provided with a depending arm 764, the lower end of which carries an adjustable screw 766 adapted to engage the back of the stop pawl 744 and move the pawl into active 120 position as the lever 758 rides up the cam 756. When the pawls are moved into active position they are retained in this position by a latch 768 mounted to turn on the shaft 762 and drawn forward into active 125 position by the spring 770. The latch 768 is disengaged from the stop pawl to release the pawl and thus engage the clutch 718 by the mechanism which causes the driving 130

clutch 720 for the cam sleeve to be disengaged through mechanism which will be later described. The timing shaft 748 is driven from the sleeve 730 through gearing 772 which is so proportioned that the shaft makes a complete revolution for each one and one-half revolutions of the sleeve 730, and therefore every one-half revolution of the cam shaft 518. When the latch 768 is operated to release the pawls and engage the clutch 718, the pawls will remain in inactive position while the shaft 748 is making a complete revolution, at the end of which the lever 758 will ride up on to the high part of the cam 756, returning the pawls to stopping position, and as the clutch 718 is disengaged and the rotation of the shaft ceases, the lever will pass off of the abrupt shoulder at the end of the cam and will be returned to the position indicated in Fig. 48 by the spring 774.

The return of the lever as the clutch 718 is disengaged is utilized to trip the stop pawl 776 and rebound pawl 778 for the clutch 720 and thus cause the engagement of this clutch. The tripping mechanism comprises a pawl 780 pivoted on the lever 758, and so arranged that the upward movement of the lever in moving the stop pawl 744 into stopping position carries the lower end of the pawl up above the end of an arm 782 which is secured to the rock shaft 762 (Fig. 44). The pawl is pivoted on the lever, and its upper end is held by a spring against the vertical face of the bar 784, so that the lower end of the pawl may yield as it passes the arm 782, and may then snap into position above the arm. When the lever rides off the end of the cam, the pawl acts to depress the arm 782 and rock the shaft 762, and then the continued downward movement of the pawl disengages it from the end of the arm so that the shaft is free to return to normal position. The rock shaft carries the latch 786, which retains the stop and rebound pawls 776 and 778 in active stopping position until disengaged from the stop pawl by the rocking of the shaft 762. The stop and rebound pawls are mounted to swing on the timing shaft 788 for the clutch 720, and when the latch 786 is tripped they are moved into inactive position by a spring 790 secured to the upper end of the stop pawl. This engages the clutch 720 and starts the rotation of the cam sleeve. The timing shaft 788 is driven from the sleeve 736 through gearing 792 which is so proportioned that the shaft makes one revolution for one and one-half revolutions of the sleeve, and therefore makes one revolution for each revolution of the cam sleeve 274.

The mechanism for returning the pawls to inactive position and thus disengaging the clutch 720 and stopping the rotation of

the cam sleeve is so constructed that it may be readily adjusted to disengage the clutch after the cam sleeve has made one or any desired number of revolutions. The means for securing this result comprises a worm 794 secured to the timing shaft 788 and arranged to be engaged by a follower on the lower end of an arm 796 depending from the left-hand hub of a frame 798 which is mounted to slide and rock on the shaft 762 (Fig. 42). The frame is provided with a second hub 800 having a gear segment 802 which engages an elongated segment 804 formed on the hub of the stop pawl 776 (Fig. 40). The means for rocking the frame comprises a lever 806 mounted to turn on the left hub of the frame 798, and having a yielding connection with the arm 796 formed by a spring 808 arranged between a projection 810 on the lever and nuts 812 on a stud 814 which extends from the arm through a hole in the projection. The travel of the frame 798 along the worm 794 brings the lever 806 into the path of a pin 816 which projects from the gear 792 on the end of the timing shaft, and is arranged to swing the lever and the frame 798 away from the shaft, or in a direction to disengage the arm 796 from the worm, and to swing the stop pawl 776 into stopping position. A spring 818 tends to move the frame 798 toward the right in Fig. 42 when the arm 796 is disengaged from the worm. The movement of the frame in this direction is delayed, however, until the clutch 720 is disengaged and the parts driven thereby brought to rest by a spring operated latch lever 820, the end of which snaps in front of the hub of the lever 806 as the frame reaches the limit of its travel toward the left in Fig. 42. The other end of the lever is arranged to be engaged by the outer end of the rebound pawl 778 when this pawl is moved into locking engagement with the rebound stop disc by the spring-pressed pin 822 as the parts driven by the clutch 720 are brought to final stopping position. When the stop pawl thus operates the latch lever 820, the frame 798 is released and is moved quickly to the right in Fig. 42 to a position determined by the adjustment of a stop sleeve 824 which surrounds the shaft 762 and is arranged in position to be engaged by the left hub of the frame 798. The stop sleeve is carried by a slide bar 826, which is provided at its left end with a guiding hub or sleeve 828 surrounding the shaft 762. The bar and connected stop sleeve are adjusted by a hand lever 830 carrying a spring locking pin 832 adapted to engage any one of a series of positioning holes 834, and connected by a pivot pin 836 with the bar. As shown, the mechanism is so constructed that the cam sleeve 274 may be given one to three revolutions each time

its driving clutch is engaged, and in Fig. 42 the stop sleeve is shown in position for giving the cam sleeve three revolutions. When thus adjusted the stop sleeve 824 arrests the movement of the frame 798 in such position that the end of the arm 796, when engaged with the worm 794, will travel along the worm during three revolutions before the lever 806 is brought into 10 the path of the stopping pin 816.

When the frame 798 is returned to initial position by the spring 818 upon the stopping of the parts driven by the clutch 720, the latch 768 is tripped to release the stop 15 and rebound pawls 744 and 746 to engage the clutch 718 and start the rotation of the parts driven thereby. The tripping mechanism comprises a pawl 838 similar to the pawl 780, which is carried on one arm of 20 a lever 840, and is arranged to engage and depress a horizontal arm 842 projecting from the hub of the latch 768. The other arm of the lever 840 is connected by pivot pins 844 and link 846 with one arm of a bell 25 crank lever 848 (Fig. 44). The other arm of the bell crank lever is connected by a link 850 to one arm of the lever 852, the other arm of which carries a pin engaging a groove in a sleeve 854 mounted to slide on 30 the shaft 762. A spring 856 normally holds the lever 848 in engagement with a stop pin 858. During the last part of the travel of the frame 798 toward the left, the right-hand hub of the frame engages the sleeve 35 854 and carries it to the left, thus rocking the lever 848 against the tension of the spring 856, and rocking the lever 840 to carry the pawl 838 up above the arm 842 of the latch 768. When the frame 798 is 40 released and returns to position against the stop sleeve 824, the sleeve 854 is released and the spring 856 returns the levers 848 and 840 to normal position, thus moving the pawl 838 downward so that it acts to dis- 45 engage the latch 768 to engage the clutch 718, and then immediately releases the latch so that it is free to be returned to active position by its spring.

The controlling and timing mechanism 50 thus far described engages each clutch as the other is disengaged, and is adapted to secure the uninterrupted alternate rotation of the cam shaft 518 and cam sleeve 274. In addition to this automatic control, a 55 manual control is also provided which when operative will arrest the driving mechanism after each complete cycle of operations. This mechanism comprises a stop pawl 860 and a rebound pawl 862 arranged to 60 engage the roll controlling and rebound stop discs of clutch 718. The stop pawl is secured upon a rock shaft 864, and the rebound pawl is loosely mounted on the shaft and is yieldingly connected with the stop 65 pawl through a laterally projecting pin 866

held in engagement with the back of the stop pawl by the spring 752 (Figs. 43 and 48). A lever 868 is secured to the left end of the rock shaft 864, and is connected by a link 870 with one arm of a bell crank lever 872 which is mounted to rock on the shaft 694, and is connected by a rod 874 with a treadle 876 (Figs. 4, 6 and 8). A spring 878 acting on the treadle rod 874 tends to hold the pawls 860 and 862 in active stopping position. When the treadle is depressed the pawls are raised into inactive position indicated in Fig. 48, and will be retained in this position until the treadle is released. The treadle may be latched in depressed position by a latch 880 arranged where it may be conveniently disengaged or rendered inoperative by the operator at will. Whenever the pawls are moved from active position by depression of the treadle their return to active position before a complete cycle of operations has been performed is prevented by a timing cam 882 secured to the shaft 748 and arranged to engage a roll on the lever 868 (Fig. 50). The cam is so shaped that the high part of the cam will retain the pawls in raised inactive position until the timing shaft has nearly completed a revolution, after which the low part of the cam will pass under the lever 868, permitting the pawls to return to active stopping position, in case the treadle has meanwhile been released.

The treadle controlled stopping pawl 860 is arranged to disengage the clutch 718 and bring the cam shaft to rest immediately 100 after the jack shifting cam has operated to move one jack from working to receiving position, and to bring the other jack from receiving to working position. The general 105 operation of the machine, when the treadle is operated to start the operation of the machine, is as follows. When the stop pawl 860 is operated by the depression of the treadle to engage the clutch 718, the clutch makes three-quarters of a revolution, turning the cam shaft 518 through a quarter revolution, and then the clutch is disengaged by the stop pawl 744. During this quarter turn of the cam shaft the feeler finger is 110 operated, and if it finds a shoe on the jack which is in working position, the tool withdrawing mechanism and the coupling shifting mechanism is operated to cause the tools to move forward into engagement with the shoe, and to connect the feed cams with the traversing mechanism for this set of tools. The rotation of the cam shaft is then arrested by the disengagement of the clutch 718, and the clutch 720 is engaged to start 115 the cam sleeve 272. The cams on the cam sleeve then act to feed and steer the tools. The feed cams are so shaped that the fore-part and toe tools move back and forth along the sole edge once, and the shank tools 120

125 130

move back and forth along the sole edge twice for each rotation of the cam sleeve. After the cam sleeve has made one, two or three revolutions, according to the adjustment 5 of the timing mechanism, the rotation of the sleeve is arrested by the disengagement of the clutch 720, and the rotation of the cam shaft 518 is again started by the engagement of the clutch 718. This clutch 10 then makes a second three-quarters of a revolution, turning the cam shaft through a second quarter revolution, and bringing the parts back to initial position when the clutch is disengaged and the rotation of the cam 15 shaft arrested by the treadle controlled stop pawl 860. During this second quarter revolution of the cam shaft, the cams thereon operate the tool withdrawing mechanism to withdraw the tools from engagement with 20 the shoe edge and then shift the jacks, after which the shaft stops. If the treadle controlled pawl has not been returned to active position, the clutch 718 remains in engagement through an additional three-quarters 25 of a revolution, thus turning the cam shaft through one-half instead of one-quarter of a revolution, and then again starting the rotation of the cam sleeve. If there is no shoe 30 on the jack which is in working position when the feeler lever is operated, the operation 35 of the tool withdrawing mechanism to cause the engagement of the tools with the shoe, and the operation of the shifting mechanism for the coupling hooks to connect the tool traversing mechanisms with the feed 40 cams, is prevented, and the tool carriages remain stationary in retracted position until a jack is brought into working position with a shoe thereon.

40 The mechanisms for driving the various continuously running shafts of the machine are as follows. The driving shaft 712 is driven from the driving pulley 884 which is loosely mounted on the shaft beside the loose 45 idle pulley 886, and is connected with the driving shaft through speed reducing gearing 888 (Fig. 9).

The screw shafts for shifting the heel and forepart gages are driven through a shaft 50 890, the lower end of which is geared to the end of a shaft 712, and the upper end of which is geared to a transverse shaft 892 (Figs. 1, 3, 5, 17 and 18). The shaft 892 is connected through spiral gears 894 with two 55 shafts 896, which are in turn connected with two sets of worm shafts through gearing 898.

The shaft 258 which rotates the tool vibrating shafts for the forepart tools, and the 60 shaft 330 which rotates the vibrating shafts for the shank and toe tools, are driven from a sprocket wheel 900 on the hub of the driving pulley through a chain 902 (Figs. 2, 3 and 9). The chain passes over a sprocket 65 wheel on a short shaft 904 geared to a ver-

tical shaft 906 which is connected through spiral gears 908 and 910 with the shafts 258 and 330.

While the various features of the invention have been shown and described as applied to a twin edge setting machine provided with five tools or irons for simultaneously acting upon each shoe, it will be understood that various features of the invention are not confined in their application 70 either to edge setting machines or to machines provided with a plurality of tools for simultaneously operating upon each shoe, or to twin machines, and that features of the invention may be embodied with advantage 75 in other forms of edge setting machines, or in machines for performing other operations on a shoe.

What is claimed is:—

1. A machine for operating on shoes, having, in combination, a shoe support, mechanism for automatically operating on a shoe on the support, means adapted to be brought into register with the shoe on the support to effect a preliminary setting of 85 the automatic mechanism, and actuating mechanism adapted to be connected with and disconnected from said means by the operator to manually effect a preliminary setting. 90

2. A machine for operating on shoes, having, in combination, a shoe support, mechanism for automatically operating on a shoe on the support, a gage connected with said mechanism and movable into register with 100 the shoe, power driven mechanism for shifting the gage, and means for manually controlling the action of the shifting mechanism to effect a preliminary setting of the gage and automatic mechanism. 105

3. A machine for operating on shoes, having, in combination, a shoe support, mechanism for automatically operating on a shoe on the support, a gage connected with said mechanism to adjust the same and movable lengthwise of the shoe, power driven mechanism for shifting the gage, and means for manually connecting and disconnecting the gage and shifting mechanism to effect 110 a preliminary setting of the automatic mechanism.

4. A machine for operating on shoes, having, in combination, a shoe support, tools for operating on a shoe on the support, traversing mechanisms for the tools, gages connected to adjust the traversing mechanisms, and mechanism for shifting the gages in either direction arranged to be connected with or disconnected from any gage by the operator at any point within its range 115 of movement. 120

5. A shoe machine, having, in combination, automatically operating mechanism, a gage connected to adjust said mechanism, power driven mechanism for shifting the 130

- gage and means for manually connecting and disconnecting the gage and shifting mechanism to effect a preliminary manual setting of the automatic mechanism.
- 5 6. A shoe machine, having, in combination, automatically operating mechanism, a gage connected to adjust said mechanism, and mechanism for shifting the gage in either direction arranged to be connected therewith and disconnected therefrom by the operator at any point within its range of movement.
- 10 7. A shoe machine, having, in combination, automatically operating mechanism, a gage movable in opposite directions and connected to adjust said mechanism, two oppositely rotating screw shafts arranged parallel to the movement of the gage, and means for manually connecting and disconnecting the gage and either shaft.
- 15 8. A machine for operating on shoes, having, in combination, two shoe supports, mechanism for alternately moving the supports from receiving to working position, corresponding edge setting tools, and mechanism for actuating each set of tools to operate on the shoe carried by the corresponding support when in working position.
- 20 9. A machine for operating on shoes, having, in combination, two shoe supports, mechanism for alternately moving the supports from receiving to working position, corresponding sets of edge setting tools, mechanism for actuating each set of tools to operate on the shoe carried by the corresponding support when in working position, and mechanism for withdrawing each set of tools from the shoe at the completion of the edge setting operation preparatory to movement of the corresponding support to receiving position.
- 25 10. A machine for operating on shoes, having, in combination, two shoe supports, a tool corresponding to each support for operating on the shoe on that support, mechanism for alternately moving the supports from receiving to working and from working to receiving positions, mechanism for moving each tool into working relation to the shoe on the corresponding support when in working position, mechanism for actuating the tool to act progressively along the shoe, and mechanism for withdrawing the tool at the end of its operation on the shoe preparatory to the return of the shoe support to receiving position.
- 30 11. A machine for operating on shoes, having, in combination, a shoe support movable from receiving to working position, means for operating on a shoe on the support when in working position, traversing mechanism for causing the operating means to act progressively on the work, and means for preventing the traverse of the operating means in the absence of a shoe on the support when in working position.
- 35 12. A machine for operating on shoes, having, in combination, a shoe support movable from receiving to working position, means for operating on a shoe on the support when in working position, traversing mechanism for causing the operating means to act progressively on the work, means for preventing the traverse of the operating means in the absence of a shoe on the support when in working position, and means for resuming the normal operation upon the presentation of a shoe in working position.
- 40 13. A machine for operating on shoes, having, in combination, a shoe support, mechanism for moving the support from receiving to working and back to receiving position, means for operating on a shoe when in working position, and mechanism for rendering the operating means inactive during any cycle in which the support is moved into working position without a shoe thereon.
- 45 14. A machine for operating on shoes, having, in combination, a shoe support, mechanism for moving the support from receiving to working and back to receiving position, means for operating on a shoe when in working position, and mechanisms for rendering the operating means inactive during any cycle in which the support is moved into working position without a shoe thereon and for rendering it again active upon the presentation of a shoe in working position.
- 50 15. A machine for operating on shoes, having, in combination, a shoe support, mechanism for moving the support from receiving to working and back to receiving position, a tool for operating on a shoe when in working position, mechanism for advancing the tool to working position preparatory to and for withdrawing it at the completion of its operation on the shoe, mechanism for traversing the tool along the shoe, and means for preventing the advance of the tool into working position and the traverse of the tool during any cycle in which the support comes into working position without a shoe thereon.
- 55 16. A machine for operating on shoes, having, in combination, a shoe support, mechanism for moving the support from receiving to working and back to receiving position, a tool for operating on a shoe when in working position, mechanism for advancing the tool to the shoe preparatory to its operation thereon, and means for preventing the advance of the tool during any cycle in which the support comes into working position without a shoe thereon.

17. A machine for operating on shoes, having, in combination, a shoe support movable from receiving to working position, a tool for operating on a shoe on the support 5 when in working position, traversing mechanism for the tool, a feeler for engaging a shoe on the support when in working position, and means rendered inactive by the engagement of the feeler with the shoe for preventing the traverse of the tool.

18. A machine for operating on shoes, having, in combination, two shoe supports, mechanism for alternately moving them from receiving to working position, corresponding tools for operating on shoes on the supports when in working position, and means for preventing the operative movement of a tool during any cycle in which the corresponding support comes into position without a shoe thereon.

19. A machine for operating on shoes, having, in combination, two shoe supports, mechanism for alternately moving them from receiving to working position, corresponding tools for operating on shoes on the supports when in working position, mechanism for traversing each tool along the shoe on the corresponding support, and means for preventing the traverse of the tools during 30 any cycle in which the corresponding support comes into working position without a shoe thereon.

20. A machine for operating on shoes, having in combination, two shoe supports 35 movable alternately from receiving to working position, corresponding tools for operating on shoes on the supports, mechanism for traversing the tools along the shoe, feelers arranged to engage shoes on the supports 40 when in working position, and means rendered inactive by the engagement of a feeler with a shoe for preventing the traverse of the corresponding tool or tools.

21. A machine for operating on shoes, having, in combination, two shoe supports 45 movable alternately from receiving to working position, corresponding tools for operating on shoes on the supports movable toward and away from the supports to bring the 50 tools into and out of working relation to the shoe, and means for retaining the tool or tools corresponding to each support in retracted position during any cycle in which that support comes into working position 55 without a shoe thereon.

22. A machine for operating on shoes, having, in combination, two shoe supports, corresponding tools for operating on shoes on the supports, a feed cam for giving traversing movements to the tools, and means 60 for alternately coupling the cam with the tools.

23. A machine for operating on shoes, having, in combination, two shoe supports,

corresponding sets of tools for operating 65 on shoes on the supports, a single set of feed cams for giving traversing movements to the tools, and mechanism for alternately coupling the cams with the two sets of tools.

24. A machine for operating on shoes, having, in combination, two shoe supports movable alternately from receiving to working position, corresponding sets of tools for operating on shoes on the supports, a single set of feed cams, mechanism for alternately 75 coupling the feed cams with the tools to give traversing movements to the set corresponding to the support in working position.

25. A machine for operating on shoes, 80 having, in combination, two shoe supports movable alternately from receiving to working position, corresponding sets of tools for operating on shoes on the supports, a single set of feed cams, mechanism for alternately 85 coupling the feed cams with the tools to give traversing movements to the set corresponding to the support in working position, and means for preventing such coupling in any cycle in which the corresponding support 90 comes into working position without a shoe thereon.

26. A machine for operating on shoes, having, in combination, two shoe supports, corresponding sets of tools for operating 95 on shoes on the supports, a single set of feed cams, cam levers operated by the cams, coupling devices corresponding to each set of tools through which traversing movements 100 may be transmitted to the tools, and mechanism for alternately connecting and disconnecting the coupling devices with the feed cam levers.

27. A machine for operating on shoes, having, in combination, two shoe supports, two 105 forepart and two shank tools corresponding to each support, an independently adjustable traversing mechanism for each tool, a single feed mechanism for the forepart tools, a single feed mechanism for the shank tools, and 110 mechanism for alternately connecting the feed mechanisms with the traversing mechanisms for the two sets of tools.

28. A machine for operating on shoes, having, in combination, two shoe supports, two 115 tools corresponding to each support for operating on opposite sides of a shoe on the corresponding support, an independently adjustable traversing mechanism for each tool, a single feed mechanism, and means for alternately coupling the traversing mechanisms of the two sets of tools with the feed mechanism.

29. A machine for operating on shoes, having, in combination, a shoe support, a tool carriage for traversing the tool along the sole edge, a tool carrier mounted to swing on the carriage about an axis approximately 125

- normal to the plane of the shoe sole, and approximately in line with the point of operation, a tool holder mounted on the carrier, and mechanism for vibrating the holder.
- 5 30. A machine for operating on shoes, having, in combination, a shoe support, a tool carriage for traversing the tool along the sole edge, a tool carrier, means for swinging the carrier on the carriage to maintain the tool substantially normal to the sole edge, and means for vibrating the tool.
- 10 31. A machine for operating on shoes, having, in combination, a shoe support, a tool carriage for traversing the tool along the sole edge, a tool carrier, means for swinging the carrier on the carriage to maintain the tool substantially normal to the sole edge, a tool holder mounted to vibrate on the carrier, and mechanism for vibrating the holder.
- 15 32. A machine for operating on shoes, having, in combination, a shoe support, a tool carriage for traversing the tool along the sole edge, a tool carrier, means for swinging the carrier on the carriage to maintain the tool substantially normal to the sole edge, a tool holder mounted to vibrate on the carrier, and connections between the shaft and holder for vibrating the holder.
- 20 33. A machine for operating on shoes, having, in combination, a shoe support, a tool carriage for traversing the tool along the sole edge, a tool carrier mounted on the carriage to swing about an axis passing approximately through the face of the tool and approximately normal to the plane of the shoe sole, a tool holder mounted to vibrate on the carrier, steering mechanism for swinging the carrier, and mechanism for vibrating the holder.
- 25 34. A machine for operating on shoes, having, in combination, a shoe support, a tool carriage for traversing the tool along the sole edge, a tool carrier mounted to swing about an axis passing approximately through the face of the tool and approximately normal to the plane of the shoe sole, a tool holder mounted to vibrate on the carrier about a parallel axis, steering mechanism for swinging the carrier, and mechanism for vibrating the holder including a shaft substantially in the axis of the carrier.
- 30 35. A machine for operating on shoes, having, in combination, a shoe support, a tool carrying arm mounted to swing toward the sole edge, a support for the arm mounted to rock to traverse the tool along the sole edge, a tool carrier frame mounted to swing on the arm to maintain the tool substantially normal to the sole edge, a tool holder mounted to vibrate on the carrier frame, and means for steering the frame and vibrating the holder.
- 35 36. A machine for operating on shoes, having, in combination, a shoe support, a tool carrier arm mounted to swing toward the sole edge, a support for the arm mounted to rock to traverse the tool along the sole edge, a tool carrier frame mounted to swing on the arm to maintain the tool substantially normal to the sole edge, a tool holder mounted to vibrate on the carrier frame, and means for steering the frame and vibrating the holder.
- 40 37. A machine for operating on shoes, having, in combination, a shoe support, a swinging tool carrying arm, a finder rod mounted therein for movement normal to the shoe sole, a tool carrier frame mounted to swing about the finder rod, a steering shaft in the frame provided with a gear engaging a relatively stationary gear on the carrier arm, a tool holder mounted to slide and vibrate on the steering shaft, an arm connected to the finder and engaging the holder, a vibrator shaft in the carrying arm in line with the finder rod, and a vibrating lever pivoted on the steering shaft and connected with the vibrator shaft and with the tool holder.
- 45 38. A machine for operating on shoes, having, in combination, a shoe support, a tool carriage movable toward the shoe support, a tool holder, a finder adapted to ride on to the sole edge, and connections between the finder and holder for bringing the tool into register with the sole edge and permitting independent movement of the holder in directions normal to the sole.
- 50 39. A machine for operating on shoes, having, in combination, means for supporting a shoe, an edge setting tool, means for moving the tool toward the sole edge of the shoe to engage the tool therewith, and a finder connected to guide the tool into engagement with the sole edge and to permit limited independent movement of the tool in directions normal to the shoe sole.
- 55 40. A machine for operating on shoes, having, in combination, a shoe support, an edge setting tool, a tool holder in which the tool is mounted to rock about axes substantially normal and tangent to the sole edge, and a sole gage connected with the holder to maintain the tool substantially in alignment with the sole edge and to permit limited independent movement of the holder in directions normal to the shoe sole.
- 60 41. A machine for operating on shoes, having, in combination, a shoe support, an edge setting tool, a tool holder in which the tool is mounted to rock about axes substantially normal and tangent to the sole edge, and a finder and sole gage connected with the holder to guide the tool into engagement with the sole edge and to maintain the tool substantially in alignment with the sole edge and to permit limited independent movement of the holder in directions normal to the shoe sole.

42. A machine for operating on shoes, having, in combination, a shoe support, a tool carriage mounted to swing about an axis substantially normal to the shoe sole, a tool mounted on the carriage for movement to maintain it substantially normal to the sole edge, and differential gearing through which swinging movements are transmitted to the carriage and steering movements to the tool on the carriage. 45
43. A machine for operating on shoes, having, in combination, a shoe support, a tool carriage mounted to swing about an axis substantially normal to the shoe sole, a tool carrier mounted to swing on the carriage to maintain the tool substantially normal to the sole edge, and differential gearing through which swinging movements are transmitted to the carriage without affecting the position of the tool carrier thereon and steering movements are transmitted to the carrier during the swinging of the carriage. 50
44. A shoe machine, having, in combination, a traveling part carrying a tool, an oscillating arm provided with a radially extending slot, a movable bar having a corresponding slot, means for causing the bar to have a parallel motion, a slide having a slot at right angles to the slot in the bar, a pivot slide engaging the three slots, connections for transmitting motion from the bar to the traveling part, and means for adjusting the slide to determine the position of the pivot slide in the slotted arm. 55
45. A shoe machine, having, in combination, a traveling part carrying a tool, an oscillating arm provided with a radially extending slot, a movable bar having a corresponding slot, a pivot slide engaging the slots, means for causing the bar to have a parallel motion, means for adjusting the pivot slide and for maintaining it in adjusted position in the bar during movements of the bar, and connections for transmitting motion from the bar to the traveling part. 60
46. A machine for operating on shoes having, in combination, two shoe supports, a tool corresponding to each support for operating on the shoe on that support, mechanism for alternately moving the supports from receiving to working and from working to receiving positions, and mechanisms for actuating the tools to act on the shoe on the supports when in working positions. 65
47. A machine having, in combination, operating mechanism, a gage carriage connected to adjust said mechanism, power mechanism for shifting the carriage in either direction, a controller connected to move with the carriage, and connections operated by the movement of the controller in either direction for throwing in the power mechanism to shift the carriage in the same direction. 70
48. A machine having, in combination, an adjustable part, power mechanism for shifting the part in either of two directions, a manually operated controller connected to move with the part, connections through which movement of the controller in either direction by the operator throws in the power mechanism to shift the part in the same direction, and means for throwing the controller and connections into neutral position upon release of the controller. 75
49. A machine for operating on shoes, having in combination, a shoe support, a tool carriage mounted to swing about an axis substantially normal to the shoe sole, a tool movably mounted on the carriage and adapted to engage the sole, and means for swinging the carriage about its axis and for steering the tool on the carriage to maintain the tool substantially normal to the sole edge. 80
50. A machine for operating on shoes, having in combination, two shoe supports, a tool corresponding to each support for operating on the shoe on that support, mechanism for alternately moving the supports from receiving to working and from working to receiving positions, and mechanisms for actuating the tools to act on the shoe on the supports when in working positions. 85
